(57) **CLAIM**

The ornamental design for a hammer head, as shown and described.

DESCRIPTION

FIG. 1 is a front, top and right-side perspective view of a hammer head embodying my new design;

FIG. 2 is a rear, bottom and right-side perspective view thereof;

FIG. 3 is a left-side elevational view thereof, the right-side elevational view being a mirror image;

FIG. 4 is a front elevational view thereof;

FIG. 5 is a rear elevational view thereof;

FIG. 6 is a top plan view thereof;

FIG. 7 is a bottom plan view thereof;

FIG. 8 is a sectional view taken along the line 8-8 of FIG. 6; and,

FIG. 9 is a perspective view similar to FIG. 1, wherein the hammer head has been attached to an exemplary handle shown in phantom.

The dash lines in FIG. 9 form no part of the claimed invention.

1 Claim, 7 Drawing Sheets(56)
